(57) **CLAIM**

The ornamental design for a bag for floor care apparatus, as shown and described.

DESCRIPTION

FIG. 1 is a front, right isometric view of a bag for floor care apparatus showing our new design;

FIG. 2 is a front elevation view thereof;

FIG. 3 is a rear elevation view thereof;

FIG. 4 is a top plan view thereof; and,

FIG. 5 is a right side elevation view thereof.

Portions of the accompanying drawings that appear in phantom lines are provided to illustrate the environment of the invention and do not form part of the invention as claimed.

The crosshatch surface shading is understood to repeat throughout the indicated area.
